AUTOMATIC TELEPHONE CALLING SYSTEM

Gilbert Zahner, Maisons Alfort, and Georges Chérourvier, Vesinet, France, assignors to Societe D'Applications Nouvelles D'Electricite et de Mecanique (S. A. N. E. M.), Paris, France, a society of France

Application October 31, 1946, Serial No. 706,854
In France July 12, 1946

3 Claims. (Cl. 179—90.2)

1

The present invention relates to devices for automatically performing all the dialling operations necessary for calling certain subscribers in an automatic telephone system, these devices being brought into operation by the displacement of a control member adapted to return by itself to its initial position once the necessary impulses have been sent through the line.

The object of our invention is to provide a device of this kind which is better adapted to meet the requirements of practice than those used for this purpose up to this time and, in particular, such that the fact of keeping the control member in active position longer than is necessary can introduce no perturbation into the working of the device.

For this purpose, according to my invention, a device for automatically performing the dialling operations for calling at least one subscriber in an automatic telephone system including a call line comprises, in combination, means for sending trains of current impulses in said line, a frame, means, including at least one rotary part journalled in said frame, for determining the time and duration of said impulse trains, a manual control member movable with respect to said frame, a piece movable in said frame, unidirectional transmission means between said piece and said rotary part to transmit movement of said piece in one direction to said rotary part, a spring interposed between said piece and said control member to urge said piece in said direction in response to a displacement of said control member in a given direction of movement thereof, means movable in said frame transversely to the axis of said rotary part for locking it in a given position, spring means for urging said locking means toward active position, release means operatively connected with said control member for bringing said locking means into inoperative position in response to a displacement of given amplitude of said control member in the above mentioned given direction of movement thereof, means operatively connected with said transmission means for opposing return of said release means to their initial position as long as said locking means are in inoperative position, means operatively connected with said transmission means for automatically stopping said rotary part in the position where it is to be locked by said locking means, means for returning said control member and said transmission means into initial position in response to the return of said locking means into active position, and means operative in response to said return movement of said

2

transmission means for bringing said stopping means out of action.

A preferred embodiment of our invention will be hereinafter described with reference to the accompanying drawings, given merely by way of example, and in which:

Fig. 1 is a plan view, with the lid removed, of an embodiment of a device according to our invention;

10 Figs. 2 and 3 are sectional views on the lines II and III of Fig. 1, respectively.

The device shown by way of example includes a frame 1 in which is adjustably supported a sliding member 3 including an arm 2 and operated by means of a handle 4. Sliding member 3 is provided with a slot or window 5 through which can be read a number, letter or any other mark of a series traced on a fixed part of the frame, each number, letter, or other mark corresponding to a subscriber to be called by means of the device. This device is thus set to perform all the dialling operations for calling one of these subscribers by bringing sliding member 3 into the position for which the number, letter or other mark corresponding to this subscriber is visible through window 5.

Member 3 slides along guiding rods 6 and 7. It has a bent edge fitted with an elastically mounted finger 8 adapted to engage between the teeth of a toothed portion 9 of rod 6, so as accurately to fix the position of sliding member 3 in the frame and to keep it in this position.

A central shaft 10, parallel to the movement of member 3 and journalled in transverse plates 11 and 12 fixed to frame 1, carries a drum 13 provided with transverse grooves or slots in each of which can be fitted a control disc 14 provided with notches and projections 15 on its periphery. Each of these discs 14 corresponds to one of the subscribers that can be called by means of the device.

These discs are adapted to cooperate with a finger 16 longitudinally slidable but angularly fixed on a shaft 17 parallel to shaft 10 and journalled in end plates 11 and 12. The position of finger 16 along shaft 17 is controlled by sliding member 3. Shaft 17 carries a cam 18, made of an insulating material and adapted to control a switch 19 which, every time finger 16 is lifted, in the course of the rotation of drum 13, by the passage thereunder of a projection 15 of the disc 14 in the plane of which said finger has been set, causes the flow of current fed by wires 20 to the call line through terminals 21 to be stopped, and this for a time which depends upon the

angular length of said projection 15. Current is supplied to the device, when the receiver is taken off, through terminals 22 connected by wires 23 with a generator of impulses constituted, as well known, by a switch 24 controlled by a cam 25, also made of an insulating material and rotated in a continuous manner by the driving mechanism of the device, which will be hereinafter described. A small speed governor 26, for instance of the centrifugal mass type, controls the movement of this cam. The means for producing and transmitting impulses in automatic telephone systems are well known, and it is unnecessary to describe their construction and operation in a detailed manner.

With such a device, in order to call one of the subscribers for which the device is provided, sliding member 3 is set to the position corresponding to this subscriber, whereby finger 16 is brought into the transverse plane of the disc 14 corresponding to said subscriber. When this disc is rotated, together with drum 13, as it will be hereinafter described, finger 16 is lifted successively as many times as there are projections 15 on said disc and every time for a period corresponding to the size of the projection that is passing under said finger, so as to send through the combined actions of cams 25 and 18, the desired number of impulses into the call line.

When the device is in its initial position or position of rest, the free end of elastic finger 16 is engaged in a radial notch 27 of the disc 14 opposite which said finger has been brought by sliding member 3. All of the discs 14 are provided with respective notches 27 located all on the same line, so that sliding member 3 can be freely moved across the discs.

Drum 13, which carries control discs 14 and cam 25, may be driven through any suitable means (mechanical, electric, pneumatic, etc.). For instance, in the example shown by the drawings, the driving means include a torsional helical spring 28. One end of spring 28 bears against a lug 30 rigid with a longitudinal spindle 31 extending coaxially in spring 28 and journaled in walls 11 and 12. The other end of spring 28 bears against a lug 29 carried by an arm rigid with a sleeve 32 freely engaged on spindle 31 and arranged to be coupled for one direction of rotation, by ratchet teeth 34 with a sleeve 33 also rotatable on said spindle. Sleeve 32 is rigid with a nut-shaped portion 35 through which it is possible, by means of a spanner engaged thereon to rotate said sleeve in such manner as to tension spring 28. Rotation of sleeve 32 in the opposite direction is prevented by two cooperating rows of ratchet teeth 34 respectively carried by parts 32 and 33 and urged toward each other by spring 34! so as to couple, for one direction of rotation, sleeve 32 with sleeve 33 which, in the position of rest, is prevented from rotating in this direction, as it will be hereinafter explained.

One end of spindle 31 projects from the right-hand side of the apparatus. It carries a lever 36 fitted with a control member or key 37. On the other end of spindle 31 is keyed a sleeve 38 connected to one end of spring 34!, the other end of said spring being fixed to the frame of the device so that said spring 34! also acts as a torsional return spring for spindle 31. Sleeve 38 carries an arm 50 fitted with a transverse finger 51. This finger is intended to cooperate with an arm 47a of a piece 47 pivoted to the frame at 48 and urged in the anti-clockwise direction by a spring 49. Piece 47 includes another arm which

carries a roller 44 adapted to engage in a notch 45 provided in the end part 46 of drum 13, so as to lock said drum in position of rest.

Sector 42 is provided with an arcuate passage 52 for finger 51 so as to permit free movement of said finger with respect to said sector.

Sleeve 33 carries, fixed thereon, a toothed sector 42 in mesh with a pinion 43 coaxial with the shaft 10 of drum 13 and connected with said shaft through a ratchet wheel, so that the toothed sector can drive the drum only in one direction of rotation. The dimensions of toothed sector 42 are chosen in such manner that its cooperation with pinion 43 causes drum 13 to rotate through a whole revolution.

In the position of rest, the locking of drum 13 by roller 44 prevents any possibility of rotation of toothed sector 42 and sleeve 33 in the direction in which said sleeve is urged by spring 28.

When the operator depresses key 37, he causes arm 50 to rotate in the clockwise direction (referring to Fig. 2). At the same time, sleeve 33 is urged, through the intermediate of spring 28, to rotate in the same direction, but at this time, as above explained, the fact that drum 13, with which sleeve 33 is coupled through sector 42 and pinion 43, is locked by roller 44, prevents said sleeve 33 from moving. Therefore spring 28 undergoes a temporary increase of its tension.

As soon as finger 51 engages arm 47a and therefore disengages roller 44 from notch 45, drum 13 is released and the strength accumulated in spring 28 causes sector 42 to rotate in the clockwise direction. In this position of piece 47, a projection 53 of said piece engages finger 51 and temporarily prevents it from moving backward.

Therefore, from this time on, whether the operator keeps key 37 depressed or releases it, drum 13 is being rotated through the action of sector 42, actuated by spring 28.

Now, the right hand end plate 56 of drum 13 is provided with a rounded notch 59 adapted to accommodate a stopping member 58 of corresponding shape carried by an arm 57 pivoted to the frame of the device and subjected to the action of a spring 60 which urges stopping member 58 away from drum 13 and normally keeps arm 57 applied against an abutment 61. Arm 57 is fixed to a rod 55 parallel to shaft 10 and journaled in walls 11 and 12. To this arm is fixed an elastic plate 54 extending across the plane of sector 42 and so positioned that said sector comes into contact therewith when drum 13 has rotated through about three quarters of a circumference.

When the edge of sector 42 engages this plate 54, it transmits therethrough an anti-clockwise rotation to arm 57, gradually bringing stopping member 58 into contact with the periphery of part 56 and applying it thereon with an increasing force. When drum 13 has made a full revolution, that is to say is back into its initial position, notch 59 has come opposite member 58, which is therefore tightly engaged therein. Drum 13 is therefore automatically stopped in this position (no matter whether key 37 is still being kept depressed by the calling subscriber).

Simultaneously with this, the notch 45 of part 46 has come opposite roller 44 and the latter has been engaged into said notch by piece 47 under the action of spring 49, this movement also releasing finger 51 from the retaining action of projection 53. Spindle 31 is then returned by spring 34! to its initial position, together with arm 50, the projecting finger 51 of which in turn brings back toothed sector 42 into its initial position,

determined by its engagement with an elastic abutment 63. Operating lever 36, carried by spindle 31, is also returned in its initial position in the course of this movement.

The return of sector 42 into its initial position has released elastic plate 54 from the pressure exerted thereon by said sector, so that arm 57 has been brought back by spring 60 into contact with abutment 61.

All the parts having thus been returned into their initial positions, the device is ready for a new operation. It is pointed out that this result is obtained without any risk of a mistake of the subscriber getting the device out of order and that the drum is automatically stopped after it has rotated through 360° even if, at this time, operating key 37 is still being depressed by the calling subscriber, because the stopping is performed by auxiliary stopping means 58 automatically brought into action by sector 42 once it has been started and wholly independent of the subscriber's moves.

Cam 25, which is to produce, in a known manner, the current impulses to be sent into the calling line, is driven through a gear transmission 64 interposed between ratchet wheel 62, mounted on pinion 43, and the spindle of said cam, so that the latter is rotated only when drum 13 is being rotated.

In a general manner, while we have, in the above description, disclosed what we deem to be practical and efficient embodiments of the present invention, it should be well understood that we do not wish to be limited thereto as there might be changes made in the arrangement, disposition and form of the parts without departing from the principle of the present invention as comprehended within the scope of the accompanying claims.

What we claim is:

1. A device for automatically performing the dialling operations for calling at least one subscriber in an automatic telephone system including a call line, which comprises, in combination, means for sending trains of current impulses in said line, a frame, means, including at least one rotary part journaled in said frame, for determining the time and duration of said impulse trains, a manual control member movable with respect to said frame, a piece movable in said frame, unidirectional transmission means between said piece and said rotary part to transmit movement of said piece in one direction to said rotary part, a spring interposed between said piece and said control member to urge said piece in said direction in response to a displacement of said control member in a given direction of movement thereof, means movable in said frame transversely to the axis of said rotary part for locking it in a given position, spring means for urging said locking means toward active position, release means operatively connected with said control member for bringing said locking means into inoperative position in response to a displacement of given amplitude of said control member in the above mentioned given direction of movement thereof, means operative by said locking means for opposing return of said release means to their initial position as long as said locking means are in inoperative position, means operatively connected with said transmission means for automatically stopping said rotary part in the position where it is to be locked by said locking means, means for returning said

control member and said transmission means into initial position in response to the return of said locking means into active position, and means operative in response to said return movement of said transmission means for bringing said stopping means out of action.

2. A device for automatically performing the dialling operations for calling at least one subscriber in an automatic telephone system including a call line, which comprises, in combination, means for sending trains of current impulses in said line, a frame, means including at least one rotary drum journaled in said frame, for determining the time and duration of said impulse trains, a manual control member movable with respect to said frame, a piece movable in said frame, unidirectional transmission means between said piece and said drum to transmit movement of said piece in one direction to said drum, a spring interposed between said piece and said control member to urge said piece in said direction in response to a displacement of said control member in a given direction of movement thereof, means movable in said frame transversely to the axis of said drum for locking it in a given position, spring means for urging said locking means toward active position, release means operatively connected with said control member for bringing said locking means into inoperative position in response to a displacement of given amplitude of said control member in the above mentioned given direction of movement thereof, means operative by said locking means for opposing return of said release means to their initial position as long as said locking means are in inoperative position, an arm movable in a plane transverse to said drum, cooperating stopping means on said arm and said drum for stopping said drum in the position where it is to be locked by said locking means, elastic means for normally holding said arm out of contact with said drum, elastic means operatively connected with said transmission means for automatically urging said arm more and more toward said drum against the action of said first mentioned elastic means as said drum is being driven by said transmission means, means for returning said control member and said transmission means into initial position in response to the return of said locking means into active position, and means operative in response to said return movement of the transmission means for bringing said second mentioned elastic means out of action.

3. A device according to claim 2 in which said drum is provided with a notch located in the plane in which said arm is moving and the cooperating stopping means on said arm and said drum consist of a projection carried by said arm, adapted to engage in said notch, and the notched portion of said drum.
